CLAIM

The ornamental design for a display screen with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a display screen or portion of a display screen with graphical user interface according to a first embodiment; and,

FIG. 2 is a display screen or portion of a display screen with graphical user interface according to a second embodiment. The outermost rectangular broken lines represent the edge of the display screen. The remaining broken lines, including all text shown, illustrate portions of the graphical user interface. None of the broken lines form part of the claimed design.
